[57] CLAIM

The ornamental design for a combined pasture pump
and watering trough, as shown.

DESCRIPTION

FIG. 1 is a perspective view taken from the front, top
and left side of a combined pasture pump and watering
trough showing my new design;

FIG. 2 is a perspective view taken from the top and
right side thereof;

FIG. 3 is a perspective view taken from the rear and left
side thereof; and

FIG. 4 is a perspective view taken from the rear
thereof.

FIG. 1

FIG. 2

FIG. 3

FIG. 4
